[57] CLAIM

The ornamental design for an agitator for automatic washer or similar article, substantially as shown.

DESCRIPTION

FIG. 1 is a side elevational view of an agitator for an automatic washer or similar article showing our new design;

FIG. 2 is a top plan view;

FIG. 3 is another side elevational view thereof, showing the agitator rotated 45 degrees from the position illustrated in FIG. 1; and

FIG. 4 is a bottom plan view.

FIG. 2

FIG. 1

FIG. 4

FIG. 3
